ATTORNEY.

UNITED STATES PATENT OFFICE

DAVID FRANKEL, OF CLEVELAND, OHIO

DESIGN FOR AN ELECTROLIER

Application filed April 29, 1929. Serial No. 31,040. Term of patent 3½ years.

To all whom it may concern:

Be it known that I, DAVID FRANKEL, a citizen of the United States, residing at Cleveland, county of Cuyahoga, State of Ohio, have invented a new, original, and ornamental Design for an Electrolier, of which the following is a specification, reference being had to the accompanying drawings, forming a part thereof.

In the drawing, the figure is a perspective showing my new design.

I claim:

The ornamental design for an electrolier as shown.

DAVID FRANKEL.
